UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

MISTREADING DEVICE FOR WEFT-REPLENISHING LOOMS.

1,186,932.

Specification of Letters Patent.

Patented June 13, 1916.

Application filed April 5, 1915. Serial No. 19,208.

To all whom it may concern:

Be it known that I, JONAS NORTHRUP, a citizen of the United States, residing at Hopedale, in the county of Worcester and State of Massachusetts, have invented certain new and useful Improvements in Mistreading Devices for Weft-Replenishing Looms; and I do hereby declare the following to be a full, clear, and exact description 10 of the invention, such as will enable others skilled in the art to which it appertains to make and use the same.

The present invention relates to an improvement in mistreading devices for weft replenishing looms.

When the filling of a newly inserted bobbin in a weft replenishing loom breaks during weft replenishing operation, the breakage is called a hopper mistread.

One object of the invention is to produce a construction which will stop the loom upon the occurrence of three successive hopper mistreads.

When the filling fails to enter the shuttle eye during the weft replenishing operation a real mistread results.

Another object of the invention is to produce a construction which will stop the loom upon the occurrence of one real mistread.

In furtherance of these objects the chief object of the invention is to produce a mistreading device of great simplicity and certainty of operation, and to this end the invention consists in the construction hereinafter described and particularly pointed out in the claims.

In the accompanying drawings illustrating the preferred form of the invention, Figure 1 is a side elevation of the left-hand end of the loom showing the attachment of the improved mistreading device thereto; Fig. 2 is a plan of the parts shown in Fig. 1; Fig. 3 is a partial front elevation of the parts shown in Fig. 1; Fig. 4 is a partial side elevation showing the mistreading device in the position for causing loom stoppage; Fig. 5 illustrates the various positions of the mistreading device during three successive hopper mistreads 50 following the operation of the weft replenishing mechanism; Fig. 6 illustrates the operation of the mistreading device during

one real mistread; and Fig. 7 illustrates the operation of the mistreading device when there is neither a real nor a hopper mistread after an indication of filling absence and the insertion of a fresh supply of filling.

The loom to which the improved mistreading device is attached, and of which the left-hand end is shown in the illustrated embodiment of the invention, may be of any usual or preferred form. The loom parts shown comprise a breast beam 10 having a shipper slot 11 provided with a recess 12 in which is received the shipper 13 during the running of the loom. A knock-off lever 14 is pivotally supported on a bracket secured to the breast beam and engages the shipper 13. The knock-off lever 14 is provided with a downwardly projecting lug which engages the front of the breast beam thereby limiting the rearward movement of the knock-off lever. A filling detector or weft fork 15 is pivotally supported on the slide 16 which reciprocates forwardly and backwardly in the slide supporting bracket 17 which is secured to the breast beam 10. The forward end of the slide 16 is provided with a boss 18 which engages the upper end of the detector arm 19 mounted upon the rock shaft 20 which extends across the front of the loom and is connected at the other end of the loom with the filling replenishing mechanism. The weft hammer 21 reciprocates forwardly and backwardly under the detector fork, and when the tail of the detector fork is depressed upon filling absence, the weft hammer engages the hook 22 depending from the tail of the fork and pushes the slide 16 forward, thereby rotating the rock shaft 20 through the medium of the detector arm 19 to set in operation the weft replenishing mechanism. When there is a filling presence on a detecting beat the detector fork is tilted, and then the forward reciprocation of the weft hammer 21 is not communicated to the slide. The above-described parts constitute the filling detecting means and the filling supply operating means, which operate in the usual manner upon the absence of filling on a detecting beat to cause the insertion of a fresh supply of filling in the shuttle.

The mistreading device is a contrivance for causing the stoppage of the loom upon the occurrence of three successive hopper mistreads or one real mistread following the operation of the filling supply mechanism. This contrivance comprises a knock-off lever actuator 25 actuated by the filling supply operating means; a stop-delaying device or tumble block 26 connected to the knock-off lever actuator 25 and supported by the upright 27 of a bracket secured to the breast beam 10; and a resetter 28 of which the function is to reset the stop-delaying device or tumble block 26 and also, under certain conditions of loom operation, to accelerate the movement of the stop-delaying device. The knock-off lever actuator 25 is pivotally connected to the detector arm at 29 and is provided on its rearward end with a lateral projection or lug 30. When the stop-delaying device or tumble block 26 is in the position shown in Fig. 4, the knock-off lever actuator 25 is lowered so that the lug 30 is dropped behind the knock-off lever 14. When the lever 25 is in this position and there is filling absence upon a detecting beat the forward movement of the detector arm 19 causes the knock-off lever 14 to disengage the shipper 13 from the recess 12, thereby knocking off or stopping the loom.

The stop-delaying device or tumble block is generally rectangular in form and is eccentrically pivoted to the knock-off lever actuator 25 at 32. On each forward movement of the detector slide 16, owing to the engagement of the weft hammer 21 with the hook 22 of the detector fork 15, the tumble block 26 is caused to travel forwardly along the upper surface of the upright 27. If a filling absence occurs during the normal operation of the loom, the corner 33 of the block 26 will come into engagement with the shoulder 36 on the upright 27 and as the block continues its forward movement it will be turned on its axis and brought into the position shown in position 1 in Figs. 5, 6 and 7. This position is always assumed by the tumble block upon the occurrence of a filling absence after a normal operation of the loom. If two successive hopper mistreads follow this filling absence, the slide 16 will be moved forward twice successively and the corners 34 and 35 of the tumble block 26 will be successively brought into engagement with the shoulder 36, thereby causing the block to be turned on its axis and brought into the position shown in Fig. 4. If now there is a third successive hopper mistread following the filling absence, the block 26 will be moved forwardly in the usual manner, but the corner 37 (which, it will be noted, is provided with a curved surface), instead of engaging the shoulder 36 will ride up over it and will not be turned

on its axis during the forward movement of the slide, for a purpose hereinafter described. It will be noted that during these successive filling absences on detecting beats the movements of the stop-delaying device 70 or block 26 were both reciprocatory and rotative, the reciprocating movement being due to the forward movement of the slide 16 and the connecting media 25 and 19, the rotative movement being due to the engagement of the corners 33, 34 and 35 successively with the shoulder 36. It will be observed that on each forward movement of the block 26 due to the successive hopper mistreads the block is turned through an angle of approximately 90°. A rotative movement is also imparted to the block 26 when there is a filling presence following an operation of the weft supply mechanism. This rotative movement is communicated to 85 the block 26 by the resetter 28 which is actuated by the weft hammer 21 whenever there is a filling presence. To effect this latter rotative movement the block 26 is provided with a laterally extending projection 90 or lug 38 which is adapted to be engaged by the resetter 28. The resetter 28 reciprocates forwardly and backwardly upon the top surface of the forward end of the slide 16 and is maintained in operative position 95 thereon by the ears 40 which project upwardly from the slide and engage the sides of the tail 41 projecting rearwardly from the resetter. The tail 41 of the resetter 28 is provided with a hook 42 projecting downwardly into the path of the motion of the weft hammer 21. Whenever there is a filling presence, and, as a result thereof, the detector fork 15 is tilted out of the path of motion of the weft hammer 21, the hook 42 100 is engaged by the weft hammer and the resetter 28 is moved forward to the position shown in position 3 of Fig. 6. The forward movement of the resetter 28 is limited by the engagement of the hook 42 with the slide 16, and the rearward movement of the resetter 28 is limited by the engagement of the shoulder 43 of the resetter against one of the ears 40. The tail 41 of the resetter 28 is prevented from upward movement by 105 the cotter pin 45 which passes through the ears 40. The forward end of the resetter is prevented from upward movement by the engagement of the foot 46 with the under surface of the shelf 47 which projects laterally from the upright 27. 110

Attention is directed to the position of the lug 38 with respect to the sliding surfaces of the block 26. Attention is also directed to the distances between these surfaces and the axis of the block. When the block is in the position shown in Fig. 4 the knock-off lever actuator 25 is lowered so that the lug 30 will engage the knock-off lever 14 upon the forward movement of the slide 16. 115

When the block 26 is in any position other than the position shown in Fig. 4, the knock-off lever actuator 25 will be raised so that the lug 30 will clear the knock-off lever on a forward movement of the slide 16. If now the block 26 is in the position shown in Fig. 1, it indicates that the loom is running normally and there is filling presence. Consequently the weft hammer 21 on its forward beat engages the hook 42 of the resetter 28 and pushes it forward. It will be observed that when the block 26 is in this position, the lug 38, which is situated close to the normal operation surface of the block, occupies a low position relatively to the resetter 28 so that as the resetter moves forward the lug 38 is received in the recess 48 of the resetter, as is shown in position 5 of Fig. 7. Consequently the resetter has no operative effect upon the stop-delaying device 26 during the normal operation of the loom.

The resetter 28 performs a double function, to wit: First, when there is a filling absence and the tumble block 26 occupies the position shown in position 1 of Figs. 5, 6 and 7, and there is a filling presence on the detecting beat following the filling absence, the resetter 28, on its forward movement, engages the lug 38 and causes the tumble block 26 to be turned through an angle of 180°, that is, to the position shown in position 4 of Figs. 6 and 7. In rotating the block 26 through the angle of 180° the resetter accelerates its movement, which is normally through an angle of only 90°, as was described in connection with the operation of the block 26 during successive hopper mistreads following a filling absence. Second, when the block 26 is in the position shown in Fig. 4, the resetter 28 on its forward movement during filling presence will engage the lug 38 and cause it to be turned through an angle of 90° to the position shown in Fig. 1, thereby resetting the block 26 to the position indicating normal operation of the loom. It is to be noted, of course, that whenever the weft hammer 21 pushes the resetter forward, the tumble block 26 is not reciprocated, as a result of which the resetter 28 may act upon the lug 38. During the accelerating operation the surface 52 of a cam projection, indicated generally by the reference character 50, on the resetter 28, engages the flat surface of the lug 38. When the resetter 28 operates to reset the stop-delaying device or tumble block 26 to its normal position, the point of the cam projection 50 engages the lug 38 and thereafter the cam surface 51 completes the resetting operation; so that, it may be said that the cam projection 50 of the resetter 28, is provided with an accelerating cam surface 52 and a resetting cam surface 51.

Referring now to Fig. 5, in which is illustrated the operation of the mistreading device during three successive hopper mistreads following an operation of the filling supply mechanism, it will be noted that position 1 indicates the position of the stop-delaying device or block 26 upon the occurrence of a filling absence during the normal operation of the loom. Owing to filling absence the detector fork 15 was not tilted so that the weft hammer 21 on its forward beat engaged the hook 22 and moved the slide 16 and the block 26 through the connecting media forward and turned the block 26 through an angle of 90° by the engagement of the corner 33 with the shoulder 36. On the return beat following the detecting beat the parts assume the position shown in position 2. A fresh supply of filling having been inserted in the shuttle and the filling having been broken during the insertion thereof, on the next detecting beat the filling absence is indicated, so that the weft hammer 21 engages the hook 22 and moves the parts forward as before. On this forward movement of the parts the corner 34 of the tumble block 26 engages the shoulder 36 so that the block is turned through an angle of 90° and brought into the position shown in position 3 of Fig. 5; and, on the return beat, the parts occupy the position shown in position 4. A fresh supply of filling having been inserted during which the filling was broken, there is filling absence on the next detecting beat, and the detector fork fails to be tilted, so that the weft hammer 21 on its forward beat engages the hook 22 and moves the parts forward as before. During this forward movement of the parts the corner 35 engages the shoulder 36 so that the block 26 is turned through an angle of 90° into the position shown in position 5, Fig. 5. On the return beat the parts occupy the position shown in position 6. It will be observed that when the parts are in this position the lug 30 is behind the knock-off lever 14. A third fresh supply of filling having been inserted in the bobbin and the filling having broken during the filling supply operation, there is filling absence on the succeeding detecting beat, so that the detector fork fails to be tilted, and the weft hammer 21 on its forward beat, engages the hook 22 and moves the parts forward causing the lug 30 to engage the knock-off lever 14 to knock off or stop the loom. Having caused the knock-off lever to disengage the shipper 13 from the recess 12, the block 26 continues its forward movement to the position shown in position 7 before the loom has come to rest. When the loom is started up after stoppage the return beat of the weft hammer 21 allows the filling supply

operating means to return the mistreading parts to the position shown in position 8.

Referring to Fig. 6, wherein is illustrated the operation of the mistreading device, on the occurrence of a real mistread, position 1 indicates that there has been a filling absence and that the weft hammer has engaged the hook of the detector fork and has moved the parts forward. Position 2 shows the position of the parts on the return beat. A fresh supply of filling having been inserted in the shuttle and the filling remaining intact, there is a filling laid in the shed on the first detecting beat following the operation of the filling supply mechanism; consequently the detector fork is tilted. As a result thereof the weft hammer 21 does not engage the filling fork hook 22, but does engage the hook 42 of the resetter, pushing the resetter 28 to its forward position, as shown in position 3. During this forward movement of the resetter the accelerating surface 52 of the cam projection 50 has engaged the flat surface of the lug 38 so as to rotate the block 26 sufficiently to allow it to assume the position shown in position 4 upon the return beat, which is the same as the position occupied by the block in position 6 of Fig. 5. The filling supply mechanism not having operated and the thread having broken on the return pick of the shuttle, filling absence will be indicated on the next detecting beat, and consequently the weft hammer will engage the hook 22 and move the parts forward to knock off the loom in the same manner as on the occurrence of the third successive hopper mistread. The return beat of the weft hammer allows the parts to assume the position shown in position 6, which corresponds to positions 6 and 8 of Fig. 5.

Referring to Fig. 7, which illustrates the positions assumed by the various parts of the mistreading device during the normal operation of the loom, position 1 indicates that there has been a filling absence and that the slide 16 has been moved forward to actuate the filling supply operating means. Position 2 shows the position of the parts on the return beat. A fresh supply of filling having been inserted and a hopper mistread not having occurred, there will be filling presence on the next detecting beat. Consequently, the detector fork will be tilted and the weft hammer will engage the hook 42 of the resetter 28 and will move it forward to the position shown in position 3. During this forward movement of the resetter 28 the accelerating surface 52 of the cam projection 50 will have engaged the lug 38 and have rotated the block 26 sufficiently to allow it to assume the position shown in position 4 on

the return beat of the weft hammer. Now, a real mistread not having occurred during the filling supply operation, there will be filling presence on the second detecting beat and the detector fork will be tilted. Accordingly, the weft hammer 21 will again engage the tail 42 of the resetter 28 and move it forward to the position shown in position 5. During the forward movement of the resetter 28, the point of the cam projection 50 will have engaged the lug 38 so as to have rotated the block 26 through an angle of 90° and have brought it into the position shown in position 6, which corresponds to the position shown in Fig. 1, which is the position of the block indicating normal operation of the loom. It will be noted, as hereinbefore described, that when the block 26 is in this position the lug 38 is low relatively to the cam projection 50 so that its cam surfaces have no operative effect upon the block, and as a result thereof, on the successive forward beats of the weft hammer and its engagement with the hook 42 during filling presence, the resetter 28 moves forward inoperatively.

It will be observed, in the foregoing description of the improved mistreading device, that upon the indication of filling absence the filling supply operating means causes the stop-delaying device or tumble block 26 to be moved from the position shown in Fig. 1 to the position shown in positions 1 of Figs. 5, 6 and 7, and that, if two successive hopper mistreads succeed this filling absence, the block 26 is operated by the filling supply operating means. If, however, there is a real mistread or a normal operation of the loom following filling absence, the block 26 is not actuated by the filling supply operating means but by the weft hammer 21. It will also be observed that if there is filling presence on a second detecting beat following filling absence, the weft hammer, by engaging the resetting device 28, causes the stop-delaying device or block 26 to be reset to normal position. So that the invention is not limited to the embodiment herein described but may be embraced in other forms within the scope of the following claims.

Having thus described my invention, what I claim is:

1. A weft replenishing loom having, in combination, filling supply operating means, a filling detector, means for causing loom stoppage and means positively connected with and actuated by the filling supply operating means, on three successive indications of filling absence, to bring the loom stoppage means into position to stop the loom.

2. A weft replenishing loom having, in combination, filling supply operating means,

a filling detector, a weft hammer, means for causing loom stoppage, and controlling means therefor positively connected with the filling supply operating means and adapted to be actuated thereby upon indication of filling absence during normal weaving and thereafter by the weft hammer if there is filling presence following filling absence, to bring the loom stoppage means into position to stop the loom.

3. A weft replenishing loom having, in combination, filling supply operating means, a filling detector, a weft hammer, means for causing loom stoppage, and means for controlling the operation of the loom stoppage means positively connected with the filling supply operating means and adapted to be actuated thereby upon indication of filling absence, and having provision for actuation by the weft hammer to restore the loom stoppage means to normal position if there are two successive filling presences following a filling absence.

4. A weft replenishing loom having, in combination, filling supply operating means, a filling detector, means for causing loom stoppage and a rectangular pivotally mounted stop-delaying device for controlling the operation of the loom stoppage means.

30 5. A weft replenishing loom having, in combination, filling supply operating means, a filling detector, a weft hammer, a stop-delaying device, and a resetting device having provision for accelerating the movement of the stop-delaying device and having provision for resetting the stop-delaying device to normal position.

6. A weft replenishing loom having, in combination, filling supply operating means, a filling detector, a weft hammer, loom stoppage means, a stop-delaying device, and a resetting device, said stop-delaying device having provision for actuation by the filling supply operating means upon the indication of filling absence and having provision for acceleration by the resetting device on the indication of filling presence following filling absence and having provision for resetting by the resetting device on a second filling presence following filling absence.

50 7. A weft replenishing loom having, in combination, filling supply operating means, a filling detector, loom stopping means, pivotally mounted controlling means therefor constructed and arranged to move longitudinally and rotatively if there is filling absence on three successive detecting beats to bring the loom stopping means into position to stop the loom.

50 8. A weft replenishing loom having, in combination, filling supply operating means, a filling detector, a weft hammer, loom stopping means, controlling means therefor constructed and arranged to move longitudinally and rotatively upon the indication of

filling absence and to be actuated rotatively by the weft hammer if there is filling presence on a detecting beat following filling absence to bring the loom stoppage means into position to stop the loom.

9. A weft replenishing loom having, in combination, filling supply operating means, a filling detector, a weft hammer, means for causing loom stoppage, means for controlling the stopping means constructed and arranged to move longitudinally and rotatively upon an indication of filling absence and thereafter to move rotatively to bring the loom stoppage controlling means into normal position if there is filling presence on two detecting beats following filling absence.

10. A weft replenishing loom having, in combination, filling supply operating means, a filling detector, a weft hammer, means for causing loom stoppage, a stop-delaying device for controlling the loom stoppage means, a resetting device for actuating the stop-delaying device having a cam projection provided with a resetting surface and an accelerating surface, said resetting device having provision for actuation by the weft hammer.

11. A weft replenishing loom having, in combination, filling supply operating means, a weft hammer, means for causing loom stoppage, and means controlling the operation of the loom stoppage means positively connected with the filling supply operating means and adapted to be actuated thereby when filling is absent at the side of the loom opposite the filling supply operating means, and having provision for actuation by the weft hammer if filling is present on the side of the loom opposite the filling supply operating means following filling absence.

12. A weft replenishing loom having, in combination, filling supply operating means, a weft hammer, means for stopping the loom, and means for controlling the operation of the loom stopping means positively connected with the filling supply operating means and adapted to be actuated thereby when filling is absent at the left-hand side of the loom, and having provision for actuation by the weft hammer to restore the loom stopping means to normal position if filling is present twice in succession following filling absence at the left-hand side of the loom.

13. A weft replenishing loom having, in combination, filling supply operating means, a weft hammer, means for stopping the loom, a stop delaying device having provision for actuation when filling is absent at the left-hand side of the loom, and a resetting device having provision for doubling the movement of the stop delaying device if filling is present immediately after the first absence of filling at the left-hand side of the

loom, and having provision for resetting the stop delaying device to normal position.

14. A weft replenishing loom having, in combination, filling supply operating means, 5 a filling detector, a weft hammer, means for causing loom stoppage, a stop delaying device for controlling the loom stoppage means, and a resetting device, said stop delaying device having provision for actuation 10 by the filling supply operating means on filling absence and for actuation by the resetting device on filling presence, following filling absence.

15. A weft replenishing loom having, in combination, filling supply operating means including a rock shaft, an arm rigidly secured thereto, and a lever pivoted on the

arm, a filling detector, a weft hammer, means for causing loom stoppage, a stop delaying device pivoted on the lever for controlling the loom stoppage means, and a resetting device adapted to be actuated by the weft hammer having provision for operative connection with the stop delaying device, said stop delaying device being constructed 25 and arranged to have a normal movement on filling absence by the filling supply operating means and an accelerated movement on filling presence following filling absence by the resetting device.
